Robert Bates

UNITED STATES PATENT OFFICE.

ROBERT BATES, OF PHILADELPHIA, PENNSYLVANIA.

INSTRUMENT FOR THE CURE OF STAMMERING.

Specification of Letters Patent No. 8,394, dated September 30, 1851.

To all whom it may concern:

Be it known that I, ROBERT BATES, of the city of Philadelphia, State of Pennsylvania, have invented a new and useful 5 Method by Instruments for the Cure of Stammering, and that the following is a full, clear and exact description of the principle or character which distinguishes my method of instruments from all other 10 things before known and of the manner of making, constructing, and using the same, reference being had to the accompanying drawings, making part of this specification, in which—

15 Figures 1 and 2 show perspective views of the mouth instrument, and Fig. 3 represents a section of the roof of the mouth with the instrument in place; and Fig. 4 shows a perspective view of the throat instrument, 20 and Fig. 5 shows the throat instrument in place. The same letters indicate different views of the same part.

The nature of my invention consists in the 25 employment of a tube in the mouth for the passage of air from the mouth when the muscles, that close the orifice of the mouth and stop the egress of air in speaking, are suddenly contracted by spasmodic action; and in the employment of a strap around 30 the throat, provided with a spring pad regulated by a screw, which pad presses against the throat and keeps the glottis or larynx of the throat open; thereby allowing a free passage of air through the throat and 35 mouth from the lungs; the arrest of which air by the spasmodic action of the throat and mouth causes stammering, and its escape by means of my instruments cures the spasmodic action and consequently cures 40 stammering.

In the accompanying drawings (a) represents a flattened tube open at each end; this flattened tube is shaped to fit the roof of the mouth and is about seven eighths of 45 an inch long, about three eighths of an inch from edge to edge inside, and about one sixteenth of an inch from side to side; it extends down to the teeth where it can be fastened by passing a small wire (b) between the teeth as shown in Fig. 3. By the 50 application of this, when the tongue is pressed against the roof of the mouth or teeth, as in making the lingual or dental sounds, and speech is prevented by an un-

due or spasmodic action of the muscles 55 tending to stop the air, the air has free access through the tube above named, and the patient is at once relieved and is enabled to articulate. To relieve the patient in the labial sounds where the lips are so compressed as to prevent the escape of air there is an additional extension (c) of the tube which projects outward between the lips so that they cannot be closed air tight, this extension piece is, for convenience, to be 60 slipped on, and off of the piece (a) when desired. The guttural sounds, it is well known, may be freely enunciated by a pressure of the hand on the glottis or larynx, or by grasping the throat with a gentle pressure just above the collar bone; but I have enabled the guttural sounds to be uttered by my methods of instruments as follows: Besides the use of the tube just now described I have a belt, Fig. 4, (d) made of 65 patent or glazed leather lined with morocco, or made of other strong material, which is secured around the neck by means of a buckle behind as in the ordinary stock. In the front part of this belt is set a metallic 70 plate, Fig. 5 (e dotted line,) through which the regulating screw (f) passes; inside of the circuit of the strap is a metallic spring (g) covered with kid or other soft and strong material, secured at both ends by sewing to 75 the strap, with the center of this spring pad opposite the end of the regulating screw, and when the strap is put around the neck, the patient can conveniently cause the spring pad to press the glottis or larynx of 80 the throat open more or less by screwing up or unscrewing this regulating screw. The Fig. 5 shows the strap around the neck, in 85 its proper place.

By a constant use of my instruments for 95 a short time they will be found a perfect corrective. The tube can then be gradually contracted until it is closed, and the spring pad be gradually eased until the pressure of it is removed; and finally, they can 100 be removed without a return of the disease.

Having thus fully described my instruments for the cure of stammering and their application and method of use, what I claim as my invention and desire to secure 105 by Letters Patent is—

1. The employment of a tube in the mouth, which will admit of speaking and of

the passage of air when either the tongue or lips would prevent the passage of air, substantially as herein above set forth.

2. The employment of the adjustable spring pad substantially as herein above set forth.

3. The joint employment of the mouth tube and the adjustable spring pad, at the

same time curing the guttural, lingual and labial disease of stammering, substantially as herein above set forth.

ROBERT BATES.
